UNITED STATES PATENT OFFICE.

JOHN H. ROSKO, OF JOHNSTOWN, PENNSYLVANIA.

FRAUD-PREVENTING DEVICE.

1,177,448.

Specification of Letters Patent. Patented Mar. 28, 1916.

Application filed July 17, 1915. Serial No. 40,494.

To all whom it may concern:

Be it known that I, JOHN H. ROSKO, a citizen of the United States, residing at Johnstown, in the county of Cambria and State of Pennsylvania, have invented certain new and useful Improvements in Fraud-Preventing Devices, of which the following is a specification.

This invention relates to new and useful improvements in fraud preventing devices.

The primary object of this invention is to provide an automatically operable fraud-preventing device upon the alarm box of a fire alarm system and whereby the arm of any person sending in an alarm is automatically grasped so that such person is held a prisoner until released by an officer of the department. It will be seen that by such a provision, if any person should send in a false alarm, he would be arrested by the officer when the officer discovered such an illegal act on the part of the person giving the alarm.

A further object is to prevent false alarms in fire alarm systems by providing upon the alarm box a means for retaining the actuator thereof so that persons knowing of the existence of the device are advised that their certain arrest will follow any attempt at sounding a false alarm.

A still further object is to prevent the expense and annoyance to fire departments which are commonly caused by sending in false alarms, such object being accomplished by arranging an automatically closed hand-cuff adjacent the hand entrance opening of the alarm box, such hand-cuff being releasable upon the actuation by means of an operating key.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like designating characters refer to corresponding parts throughout the several views:—Figure 1 is a central vertical transverse view through a fire alarm box provided with the device illustrated in its open set position. Fig. 2 is a similar view partially broken away with the elements in their released locking posi-

tions. Fig. 3 is an inner elevational view of the trip and switch upon a rear plate within the alarm box. Fig. 4 is a top plan view of the device with the top of the casing removed. Fig. 5 is a perspective view of the hand-cuff members detached and separated. Fig. 6 is a vertical sectional view of the lock taken upon line VI—VI of Fig. 7. Fig. 7 is a perspective view of the fire alarm box. Fig. 8 is a perspective view of the spindle member of the lock. Fig. 9 is a perspective view of the spindle carried releasing means. Fig. 10 is a perspective view of the releasing means and spindle assembled. Figs. 11 and 12 are perspective views of the inner end portions of the latch actuating rods, and Fig. 13 is a perspective view of the operating key employed with the device.

It will be first understood that the present attachment is designed for use with a fire alarm box 15 of substantially the usual construction, the same being placed at any desired point or street corner and being provided with switch terminals 16 within the box upon the plate 17 of an inclosing frame 21 therein. A switch lever 18 is secured to a switch shaft 19 which is journaled through a brace 20 and the frame plate 17 and a turn knob 22 is secured to the inner end of the switch shaft 19 for manually closing the said switch.

The front wall 23 of the alarm box is provided with an entrance opening 24 for allowing a person to insert his hand for the purpose of turning in a fire alarm by turning the knob 22 to close the circuit switch. A swinging closure door 25 is provided for the front entrance opening 24 and a readily releasable catch 26 is provided for the said door.

The aforementioned frame 21 has a casing 27 at its forward side having a U-shaped cut-away portion 28 adjacent the box opening 24. The wrist-engaging hand-cuff members 29 and 30 are slidably mounted in their interlocked positions within the casing 27 having the lower ends of semi-circular wrist-encircling portions 31 slidably arranged upon a guide-way 32 arranged horizontally within the casing 27 and beneath the cut-away portion 28 thereof. The said curved members 31 are provided with centrally projecting toothed racks 33 extending horizontally in opposite directions and being provided with transversely projecting pins 33

slidably mounted in horizontal slots 34 of the said casing 27, the said racks being provided with teeth 35 upon the upper sides, it being understood that the said racks are 5 slideable outwardly and inwardly of the said casing.

Spring-pressed dogs 36 are pivoted as at 37 within the casing 27 at its opposite sides thereof and are normally retained in engagement with the rack teeth 35 of the hand cuff members, as best illustrated in Fig. 1, and in which position it will be seen that the dogs 36 allow the hand-cuff members to freely 10 close but prevent any opening thereof by restraining any outward movement of their racks 32. Angular operating levers 38 are provided for each of the dogs 36 being pivoted to the said casing as at 39 and having their inner ends connected by links 40 with 15 the inner ends of the said dogs while the outer ends of the levers 38 are connected by means of links 41 with the shorter outwardly projecting arms of rocker arms 42 pivoted upon pins 43 upon the inner side of the casing 27, the operating means for each of the 20 said dogs being identical although oppositely arranged.

A spindle 44 is transversely journaled through the casing 27 and the said spindle 25 is provided adjacent its inner end which projects through the casing and into the alarm box with a concentrically arranged disk 45 having a keeper socket 46 therein while oppositely-projecting eccentrically mounted 30 disks or cams 47 are secured to the spindle 44 at the opposite sides of the disks 45. Similar eccentric rods 48 and 49 have their outer ends pivotally connected to the longer 35 arms of the rocker arms 42 while their inner ends are provided with heads 50 having circular perforations 51 therein for journaling the inner ends of the said rods upon the 40 aforementioned cam disks 47.

A sleeve 52 is journaled upon the spindle 44 and has a cross-head 53 mounted thereon 45 between the eccentric rod connection and the adjacent side wall of the casing 27. A key-hole plate 54 is secured to the outer end of the spindle 44 and is revolvably-mounted 50 within a circular opening 55 in the front wall of the alarm box directly beneath the entrance opening 24 of the latter, the said plate 54 being provided with oppositely-arranged circular openings 55 adapted for the 55 reception of the opposite wards 56 of an insertible key 57. The sleeve 52 is provided with opposite notches 58 upon its outer edge and it will be understood that by inserting the key wards 56 within the plate opening 60 55, the spindle 44 may be revolved irrespective of the sleeve 52 but that when the openings 55 of said plate are brought into alignment with the notches 58 of the said sleeve, the key may be further inserted for positioning such wards 56 within the sleeve 65

notches 58 and whereupon a turning of the key will revolve not only the spindle 44 but also the sleeve 52 with its cross head 53.

A post 59 is mounted upon the inner wall of the casing 27 and is provided with a leaf spring 60 secured to its inner end while a locking lug 61 projects from the spring 60 and is normally engaged with the adjacent face portion of the disk 45 by means of the said spring. It will thus be evident that upon turning the disk 45, the keeper socket 46 will be brought into alignment with the locking lug 61, which lug will thereby seat itself within the said socket for preventing any further turning of the disk 45 as well as the spindle 44 and the key plate 54. The spindle 44 has a central bore 62 extending therethrough and being adapted at its outer end for the reception of a central relatively longer ward 63 of the key 57. The free end 70 of the aforementioned spring 60 is provided with a releasing rod 64 angularly projecting therefrom and slidably mounted within the bore 62 projecting thereinto from the inner end of the said bore, as best illustrated in 75 Fig. 6.

Means for closing the hand-cuff members 29 and 30 are provided consisting of levers 64 pivoted to the casing 27 by means of the aforementioned pins 43, each of the said 95 levers having a longitudinal slot 65 in its upper free end slidably receiving the pins 33 therein of the operating racks 32 of the said hand-cuff members. Operating springs 66 are carried by posts 67 attached to the 100 frame 21, the outer ends of the said springs being anchored as at 68 to the said frame while the inner ends thereof are arranged within sockets 69 upon the levers 64, the spring 66 tending to normally project the 105 racks 32 inwardly for closing the hand-cuff member. Connecting wires 70 are pivotally attached to the lower free ends of the levers 64 and the outer ends of the cross-head arms 71.

A trip rod 71 is vertically slidably mounted within brackets 73 and 74 secured to the aforementioned frame plate 17 while a collar 75 is secured to the said trip rod having a slot and pin pivotal connection 115 with an arm 79 of the switch shaft 19. The trip rod is normally held elevated by means of an encircling helical spring 77 seated upon the aforementioned bracket 74 and engaged at its upper end with a shoulder 78 of the said trip rod and whereby the switch arm 18 is normally held with the switch in its open position. Oppositely-positioned parallel shafts 79 are journaled through the frame 21 and are provided with pawls 80 adapted to be brought beneath shoulders 81 upon the inner edge of the lever 64 when the hand-cuff members are in their open separated positions as shown in Fig. 1. Inwardly-arranged arms 82 are carried by the 120 125 130

shaft 79 adjacent the frame plate 17 and are pivotally connected by means of links 83 with a cross-piece 84 carried by the trip rod 72.

5 From this detailed description of the device, it will be seen that the elements being normally positioned as illustrated in Fig. 1, allows any person to freely pass his hand through the front opening 24 of the alarm 10 box 15 after first opening the closure door 25 so that the knob 22 may be turned for closing the electric switch members 18 and 16. This movement of the shaft 19 shifts the arm 79, thereby longitudinally shifting 15 the trip rod 72 downwardly and compressing the spring 77 and this action also slightly turns the transverse shafts 79 by means of the connections 82, 83 and 84 so as to inwardly move the pawls 80 and release the 20 same from the levers 64. The levers 64 being thus released, the operating springs 66 thereof force the hand-cuff members 29 and 30 inwardly to their positions illustrated in Fig. 2, and thereby inclosing the wrist of 25 the person sending in the alarm. The racks 32 moving inwardly during this operation and in a ratcheting movement beneath the dogs 36, the said dogs prevent the reverse or opening movement of the hand cuff 30 members and thus hold the operator a prisoner, it being noted that while this operative movement just described moves the lever 64 and the sleeve 52, it does not influence the spindle 44 for releasing the dogs 36 but 35 allows the latter to remain active. The key 57 is then employed, the central ward 63 thereof being inserted within the outer end of the bore 62 presses against the releasing rod 64 and moves inwardly the spring 60 40 releasing the lug 61 from the disk opening 46 and the wards 56 being at such time positioned within the key plate openings 55, a turning of the key readily turns the spindle 44. As soon as the plate openings 55 are 45 brought into alignment with the sleeve notches 58, the key is pressed farther inwardly, positioning the key wards 56 within the said notches as best illustrated in Fig. 6. It will thus be seen that the key having 50 released the spindle, the same is turned through the agency of a key within the key plate to position the cam disks 47, opposite to that illustrated in Figs. 1 and 2 of the drawings and with the dogs 36 released from 55 the rack teeth 35 so that a succeeding turning of the key with the wards 56 engaging the sleeve notches 58 turns the sleeve 52 and changes the position of the cross-head 53 and the hand-cuff members from that shown 60 in Fig. 2 to that illustrated in Fig. 1. During this movement, the pawls 80 slide in resilient engagement with the outer curved faces 85 of the shoulders 81, being so engaged therewith by the action of the trip 65 rod spring 77 and when the levers 64 reach

the extreme limit of their releasing movement, the pawls 80 automatically engage beneath the said shoulders 81 for retaining the hand-cuff members open as illustrated in Fig. 1 and the device is then in position to 70 be again operated, it being understood that this opening movement of the hand-cuff members allowing the pawls 80 to swing inwardly permits the spring 77 to elevate the trip rod 72 to its normal position and with 75 the switch 18 out of contact.

A housing 86 is mounted upon the alarm box 15 and is provided with a gong 87 of the usual form having an operating spring, not shown, which may be wound up and 80 readily released by means of a trip 88 for allowing the gong to operate. The said trip 88 extends downwardly through a top slot 89 in the casing 27 and is within the closing path of movement of the end 90 of the 85 hand-cuff member 30. It will thus be seen that when the hand-cuff members assume their closed position as shown in Fig. 2, the trip 88 will be shifted so that the gong 87 continues to ring until the hand-cuff 90 members are again separated which releases the trip 88 and allows the return spring 91 to again normally position the same. A pivoted cover 92 is mounted upon the front 95 of the alarm box 15 for fitting over the key plate 54.

While the form of the invention herein shown and described is what is believed to be the preferred embodiment thereof, it is nevertheless to be understood that various 100 forms, modifications and arrangements of the parts may be made without departing from the spirit and scope of the invention as claimed.

What I claim as new is:

105

1. A device of the class described, comprising a fire alarm box having a hand entrance opening therein, slidably inter-engaging hand-cuff members positioned within the box adjacent the said opening, closing means for the said hand-cuff members, key-operated opening means for the said hand-cuff members, ratchet retaining dogs for the said hand-cuff members, and key-actuated releasing means for the said dogs 110 operable simultaneously with the said key-operated opening means.

115

2. A device of the class described, comprising a fire alarm box having a hand entrance opening therein, slidably inter-engaging hand-cuff members positioned within the box adjacent the said opening, closing means for the said hand-cuff members, key-operated opening means for said hand-cuff members, ratchet retaining dogs for the said hand-cuff members, key-actuated releasing means for the said dogs operable simultaneously with the said key-operated opening means, switch throwing means within 120 said box, and locking pawls for the said 125

130

hand-cuff opening means operatively connected to the said switch throwing means.

3. A device of the class described, comprising a fire alarm box having a hand entrance opening therein, slidable inter-engaging hand-cuff members positioned within the box adjacent the said opening, closing means for the said hand-cuff members, key-operated means for opening the said hand-cuff members, switch throwing means within said box, and locking pawls for the said hand-cuff opening means operatively connected to the said switch throwing means.

4. A device of the class described, comprising an alarm having an entrance opening therein, inter-engaging hand-cuff members slidably mounted within the said box, oppositely - extending toothed operating racks for the said hand-cuff members, pivoted spring-pressed operating levers for the said racks, a spindle journaled through the sides of the said box, a sleeve journaled upon the said spindle, a cross-head secured to the said sleeve, connecting means between the opposite ends of the said cross-head and the free ends of the said levers, and key-operating means for the said sleeve and spindle.

5. A device of the class described, comprising an alarm having an entrance opening therein, inter-engaging hand-cuff members slidably mounted within the said box, oppositely - extending toothed operating racks for the said hand-cuff members, pivoted spring-pressed operating levers for the said racks, a spindle journaled through the sides of the said box, a sleeve journaled upon the said spindle, a cross-head secured to the said sleeve, connecting means between the opposite ends of the said cross-head and the free ends of the said levers, a key plate disk on the outer end of the said spindle having perforations therein, said spindle being provided with a central bore and the said sleeve having end notches adjacent the said key-plate, retaining means for the said hand-cuff members, operative connections between the said retaining means and the said spindle, and a key for said spindle and sleeve seated within the said bore, plate perforations and sleeve notches when in its operative position.

6. A device of the class described, comprising an alarm box having a hand entrance opening, oppositely positioned encircling members slidably positioned within the said box, a sleeve forwardly journaled in the said box, operative connections between the said encircling members and the said sleeve, ratcheting dog retaining means for the said encircling members, a spindle journaled in the said sleeve and provided with a central bore therethrough, operative connections between the inner end of the said spindle and the said retaining

means, and an operating key for said sleeve and spindle having a ward thereof positioned within the said bore when operatively arranged.

7. A device of the class described, comprising an alarm box having a hand entrance opening, oppositely positioned encircling members slidably positioned within the said box, a sleeve forwardly journaled in the said box, operative connections between the said encircling members and the said sleeve, ratcheting dog retaining means for the said encircling members, a spindle journaled in the said sleeve and provided with a central bore therethrough, operative connections between the inner end of the said spindle and the said retaining means, a key plate secured to the outer end of the said spindle outwardly of the said sleeve and having oppositely-arranged keeper perforations, the said sleeve having oppositely-arranged keeper notches adjacent the said key plate, and an operating key for the said sleeve and spindle having wards seated within the said bore, perforations and notches when operatively arranged.

8. A device of the class described, comprising an alarm box having a hand entrance opening, oppositely positioned encircling members slidably positioned within the said box, a sleeve forwardly journaled in the said box, operative connections between the said encircling members and the said sleeve, ratcheting dog retaining means for the said encircling members, a spindle journaled in the said sleeve and provided with a central bore therethrough, operative connections between the inner end of the said spindle and the said retaining means, an operating key for said sleeve and spindle having a ward thereof positioned within the said bore when operatively arranged, a disk carried by the said spindle having a keeper opening therein, a post within said box, a spring projecting from the free end of the said post, a locking lug carried by the said spring and normally engaging the adjacent side of the said keeper disk and being positioned in the path of travel of the keeper opening therein, and a releasing red carried by the free end of the said spring and slidably positioned within the said spindle bore and having its free end in the path of travel of the said bore-receiving ward of the key.

9. A device of the class described, comprising an alarm box having a hand entrance opening, oppositely positioned encircling members slidably positioned within the said box, a sleeve forwardly journaled in the said box, operative connections between the said encircling members and the said sleeve ratcheting dog retaining means for the said encircling members, a spindle journaled in the said sleeve and provided

with a central bore therethrough, operative connections between the inner end of the said spindle and the said retaining means, a key plate secured to the outer end of the 5 said spindle outwardly of the said sleeve and having oppositely-arranged keeper perforations, the said sleeve having oppositely-arranged keeper notches adjacent the said key plate, an operating key for the said sleeve and 10 spindle having wards seated within the said bore, perforations and notches when operatively arranged, a disk carried by the said spindle having a keeper opening therein, a post within said box, a spring projecting 15 from the free end of the said post, a locking lug carried by the said spring and normally engaging the adjacent side of the said keeper disk and being positioned in the path of travel of the keeper opening therein, 20 and a releasing rod carried by the free end of the said spring and slidably positioned within the said spindle bore and having its free end in the path of travel of the said bore-receiving ward of the key.

10. A device of the class described, comprising an alarm box, hand-cuff members mounted therein, an operating sleeve for said hand-cuff members, controlling dogs for the said hand-cuff members, a controlling spindle for said controlling means 25 journaled within said sleeve and having a longitudinal bore therethrough, a disk carried by the said spindle having a keeper opening therein, a spring-pressed lug resiliently seated within the said keeper opening, 30 a releasing rod for the said lug slidably mounted within the said bore, and a releasing key for the said rod having a ward thereof slidably arranged within the said bore within the path of movement of the 35 said releasing rod.

In testimony whereof I affix my signature in presence of two witnesses.

JOHN H. ROSKO.
